9 Claims. (Cl. 257—24)

1

This invention relates to closed feed systems for steam power plants of the class including a steam generator, a turbine, a steam condenser and the associated feed, water and steam connections, and more particularly to such feed systems incorporating a deaerator separate from the condenser.

An object of the invention is to provide an arrangement whereby such closed feed system can be operated entirely automatically in a stable and satisfactory manner and whereby two or more closed feed systems can be operated entirely satisfactorily and stably in parallel with a minimum flow of feed water into and out of the system or systems.

A closed feed system in accordance with our invention includes in its simplest form a condenser, a condenser extraction pump, an external feed tank, a deaerator into which condensate is discharged by the condenser extraction pump, a deaerator extraction pump and a boiler feed pump, and is characterised by control devices which maintain a substantially constant flow of water through the condenser extraction pump and the deaerator extraction pump at substantially predetermined constant discharge pressures at the discharges of said pumps, the discharge pressure of the deaerator extraction pump being substantially greater than the pressure due to the head of water in the feed tank or/and the pressure on the surface of that water available to cause the outflow of water from the feed tank to the boiler feed pump.

Preferably, the steam condenser is of the regenerative type devised to remove corrosive gases from the feed water passing through the condenser and thereby to ensure that the feed water removed from the condenser and discharged towards the boiler feed pump will be as free as possible from corrosive gases.

With the adoption of higher pressures in boiler installations now in use in power plants, it is essential that every possible trace of oxygen or other corrosive gases should be removed from the water before it is discharged into the boilers, and every possible precaution should, therefore, be taken to remove every trace of corrosive gases from the water and prevent any possible ingress of corrosive gases or of water contaminated with corrosive gases. For this purpose, a float-controlled valve mounted on the steam condenser is so arranged that it can pass into the condenser a quantity of water equal to the maximum capacity of the condenser extraction pump, and the condenser extraction pump is so designed

2

that its maximum capacity is equal to or slightly in excess of the maximum capacity of the boiler feed pump or pumps with which it is associated. The condenser extraction pump is so devised that it is capable of handling its maximum capacity with a water level on its suction side lower than the water level at which the float-controlled valve is full open.

The feed tank in a land power plant is normally installed at a considerable height above the condenser extraction pump and the boiler feed pump so that there is an appreciable pressure above atmosphere in the pipe between the condenser extraction pump and the boiler feed pump which prevents the ingress of air and corrosive gases into the water in the pipe line between the condenser extraction pump and the boiler feed pump. A pipe connects the feed tank to the pipe between the condenser extraction pump and the boiler feed pump to allow the boiler feed pump to draw water direct from the feed tank in the event of failure of the condenser extraction pump. The boiler feed pump operates at its maximum capacity only in case of emergency and its actual delivery varies in quantity so that there is a continuous flow of water from the condenser extraction pump discharge up the pipe connected to the feed tank. The water which is passing up towards the feed tank, however, passes back by way of the float-controlled valve into the steam condenser, so that a varying quantity of water is being continuously circulated through the float-controlled valve and repeatedly subjected to the deaerating action of the regenerative steam condenser. In normal operation, there is no flow of water from the feed tank direct into the feed system, but in the event of a stoppage of the condenser extraction pump the boiler feed pump will draw water direct from the feed tank. In normal operation the discharge pressure of the condenser extraction pump is determined by the head imposed by the feed tank and that there is no possibility of water which may be contaminated passing direct into the feed system.

Two or more steam condensing plants together with two or more feed tanks may be associated together and operated in parallel with a common pressure at the point where such condenser extraction pumps and feed tanks are connected to the suction of the several boiler feed pumps. In this way the several turbines may be operated at different loadings and the several sets can operate in parallel, the quantities of condensate formed in the condensers being discharged into

the feed system at a common marrying point and pressure.

In some power installations, as, for example, on board ship, it may not be practical or convenient for the feed tank to be arranged at an elevated position and in such cases pressure loading means may be provided to ensure a reasonable pressure above the atmosphere in the piping between the condenser extraction pump, the boiler feed pump and the feed tank.

As even when operated in the manner described regenerative steam condensers do not remove all possible traces of corrosive gases from the condensate and feed water, there is arranged in the feed system a deaerator wherein all the water which in normal operation passes to the boiler feed pump is subjected to a further deaerating action so as to ensure that all the corrosive gases in the feed water are removed before the water is delivered to the boiler. For this purpose, the water inlet to the said deaerator is connected to the discharge of the condenser extraction pump at a point between the discharge of that pump and the connection to the float-controlled valve of the steam condenser. There may be arranged in the water inlet pipe line to the deaerator a float-controlled valve with the float actuated from a water level in the base of the deaerator so that on a rise in water level in the deaerator the flow of such water into the deaerator is reduced and vice versa. The deaerator is provided with a deaerator extraction pump which delivers the deaerated feed water into the suction of the boiler feed pump. The pipe connection between the deaerator extraction pump and the boiler feed pump is also connected by a pipe to the feed tank, and in this pipe line there is provided a non-return valve which prevents any possibility of deaerated water from the deaerator being discharged back to the feed tank, whereas on failure of the deaerator or deaerator extraction pump, water can flow direct from the feed tank through the said non-return valve into the suction of the boiler feed pump, thereby ensuring the continuity of the feed supply to the boiler.

The discharge of the deaerator extraction pump is connected to the top of the deaerator whereby the deaerator extraction pump is constrained to operate at substantially constant capacity at all times and at a predetermined substantially constant discharge pressure in excess of the head of the feed tank, so that the non-return valve in the connection between the feed tank and the boiler feed pump suction is held closed in normal operation and the deaerator extraction pump discharge pressure is held substantially constant at such pressure above the deaerator pressure as will ensure the satisfactory operation of the boiler feed pump.

In modern feed systems the additive effect of pumps in series in the feed system with stable discharge pressure capacity characteristics is to give a very high total discharge pressure at no load as compared with full load pressure, thereby involving a corresponding increase in design scantlings and cost.

With the arrangement according to the invention, the rise in discharge pressure of the boiler feed pump between full load and no load is limited to the characteristic of the boiler feed pump only, and the total load of the boilers may be shared between two or more boiler feed pumps in operation in proportion to their respective designed maximum capacities. The capacity of the deaerator extraction pump is arranged to be

equal to or greater than the boiler feed pump capacity, and since the boiler feed pump never discharges at maximum capacity in normal operation, there is always a flow of water from the deaerator extraction pump into the deaerator, so that water flowing in this manner is subjected to repeated deaerating action. The return of such water to the deaerator may be controlled by a float-controlled valve with the float actuated from the water level in the deaerator so that the valve is closed as the water level rises and vice versa, or there may be provided a spring-loaded valve or a pressure-biased and controlled valve to maintain a substantially constant pressure difference across the deaerator extraction pump. Control mechanism may be provided to control the flow of heating steam to the deaerator to maintain a substantially constant pressure in the deaerator.

In the accompanying drawings Fig. 1 shows diagrammatically a boiler feed system in accordance with the invention with a high feed tank. Fig. 2 shows a boiler feed system in accordance with the invention with a low feed tank.

Referring to Fig. 1, the steam condenser 1 is of the regenerative type with a well 2 in the base of the condenser. The condenser extraction pump 3 draws water from the well 2 and discharges it through a pipe 4 which is in free connection with an elevated surge tank 5 by way of a pipe 6. The pipe 6 is connected by a pipe 7 with a float-controlled valve 8 and pipe 9 to the condenser 1, the float 10 controlling the valve 8 being arranged to rise and fall with the water level in the condenser well 2 so that the valve 8 is full open at a predetermined low water level, and closed at a predetermined high water level, and at any intermediate water level the valve 8 is in a correspondingly partially open position.

The discharge from the condenser extraction pump 3 can pass direct to the boiler feed pump 11 by way of a non-return valve 12 and pipes 13 and 14. The condenser extraction pump 3 is so designed that its maximum capacity is equal to or slightly in excess of the maximum capacity of the boiler feed pump 11. The elevated feed tank 5 is normally installed at a considerable height above the condenser extraction pump 3 and the boiler feed pump 11 so that there is an appreciable pressure above atmosphere in the pipes 4, 6, 7 and the pipes 13 and 14 between the condenser extraction pump 3 and the boiler feed pump 11, and this pressure prevents the ingress of air and corrosive gases into the water which is being delivered by the condenser extraction pump 3 to the boiler feed pump 11. The condenser extraction pump 3 is so designed that it is capable of handling its maximum capacity with a water level in the condenser well 2 below the low predetermined water level at which the float-controlled valve 8 is full open. In the event of a failure of the condenser extraction pump 3 the boiler feed pump 11 can draw water direct from the feed tank 5 by way of the pipe 6, non-return valve 12 and pipes 13 and 14. The boiler feed pump 11 operates at its maximum capacity only in case of emergency and its actual delivery varies in quantity so that there is a continuous flow of water from the condenser extraction pump 3 by way of the pipe 6, pipe 7, float-controlled valve 8 and pipe 9 to the condenser 1. There is, therefore, a varying quantity of water being continuously circulated and therefore repeatedly subjected to the deaerating action of the regenerative steam condenser 1. It will be observed that in normal operation there is no

flow of water from the condenser extraction pump to the feed tank and that there is no flow of water from the feed tank 5 direct into the feed system. Any water which may be taken from the feed tank 5 must pass by way of the pipe 1 and float-controlled valve 3 into the condenser 1 wherein it is subjected to the deaerating action of the condenser. The float-controlled valve 3 is made to pass a quantity of water equal to the maximum capacity of the condenser extraction pump 3 when the float 10 is at the low level.

It will be seen that, in normal operation, the discharge pressure of the condenser extraction pump 3 is determined by the head imposed by the feed tank 5 and that there is no possibility of water which may be contaminated passing direct into the feed system in normal operation, but in the event of a stoppage of the condenser extraction pump 3 the boiler feed pump 11 will draw water direct from the feed tank 5. Two or more steam condensing plants 1 together with two or more feed tanks 5 may be associated together and operated in parallel with a common pressure at the point 15 where the several condenser extraction pumps and feed tanks are connected to the suction of the boiler feed pumps. Thus, in Fig. 1 there are shown at 4A the discharge from another condensate extraction pump and at 4A the discharge from another deaerator extraction pump. This allows the several turbines driven respectively by steam from several boilers to be operated at different loadings and ensures that the various sets can operate in parallel with the quantities of condensate formed in the condensers being discharged into the feed system at a common marrying point and pressure, with no unnecessary transfer of water from feed tank to feed tank or from condenser to condenser.

To ensure that all possible traces of corrosive gases are removed from the condensate and feed water, there is arranged in the feed system a deaerator 16 and all feed water required by the boiler feed pump in normal operation is taken by way of a pipe 17 from the pipe 6 between the connecting points of pipes 4 and 7. The pipe 17 passes by way of the inlet valve 18 controlled by the float 19 into the deaerator 16 and in so doing passes through a heat exchanger 20 in which the operating steam of an air ejector 21 is condensed and led back into the deaerator through a drain trap 22. The air ejector 21 is supplied with operating steam through a pipe controlled by a valve 23, and withdraws air and other non-condensable gases from the deaerator 16, such air and non-condensable gases being discharged to the atmosphere from the heat exchanger 20 by way of the air vent pipe 24. The float 19 is actuated from a water level in a tank 25 at the base of the deaerator 16 so that on rise of water level in the tank 25 the flow of water into the deaerator is reduced and vice versa. Heating steam from any suitable source is led into the deaerator by way of a pipe 26 and control valve 27 which may be controlled to maintain a substantially constant pressure in the deaerator 16. The deaerator 16 is provided with a deaerator extraction pump 28 which delivers deaerated feed water from the tank 25 into the pipe 14 which leads the water to the suction of the boiler feed pump 11 whence the water is discharged by way of a pipe 29 to the boilers. The pipe 14 is connected by way of the pipe 13, non-return valve 12 and pipe 6 to the feed tank 5, and the discharge pressure from the deaerator extraction pump 28 maintains a substantially constant discharge pressure in the pipe

14 at a predetermined pressure in excess of the head of the feed tank 5 so that the non-return valve 12 is kept closed at all times in normal operation and prevents any possibility of deaerated water from the deaerator 16 being discharged back to the feed tank 5, but on failure of the deaerator 16 or of the deaerator extraction pump 28 feed water can flow direct from the feed tank 5 by way of the non-return valve 12 and pipes 13 and 14 to the suction of the boiler feed pump 11, thereby ensuring the continuity of the feed supply to the boilers.

A non-return valve 30 is provided on the discharge of the deaerator extraction pump 28 to prevent feed water from the feed tank 5 entering the deaerator 16 by way of the pump 28 in the event of a failure of said pump. The discharge of the deaerator extraction pump is connected to the top of the deaerator by way of pipes 31, and the quantity of water flowing through the pipes may be controlled by a valve 32 controlled by the float 33 so arranged that on a fall of water level in the tank 25 the valve 32 is closed, and as the water level rises the valve 32 is opened. The valves 18 and 32 may be combined in one valve and operated by a common float.

The capacity of the deaerator extraction pump may be equal to or greater than the boiler feed pump capacity, and, since the boiler feed pump never discharges at maximum capacity, in normal operation there is always a flow of water from the deaerator extraction pump 28 by way of the pipe 31 into the deaerator 16 and water flowing in this manner is subjected to a repeated deaerating action. This arrangement has the advantage that the deaerator extraction pump is constrained to operate at substantially constant pressure at all loads of the boiler feed pump, thereby reducing the rise in discharge pressure at the boiler feed pump discharge between full load and no load to that determined by the characteristic of the boiler feed pump only. The arrangement is such that two or more boiler feed pumps 11 can operate stably and satisfactorily in parallel at all loads, sharing the total load in proportion with their head capacity characteristics. All feed water which is discharged to the boilers is subjected to the double deaeration of the condenser followed by the deaerator and in each of these units some of this feed water is subjected to repeated deaeration, thereby ensuring the removal of all corrosive gases at all loads. Further, both the condenser extraction pump 3 and the deaerator extraction pump 28 are constrained to operate at substantially constant discharge pressures and with suction heads which are in excess of their cavitating free suction heads, thereby ensuring stability in operation and freedom from gulping and ensuring that two or more feed systems will operate stably and satisfactorily at all loads with a minimum rise in feed pump discharge pressure from full load to no load. The discharge pressure of the deaerator extraction pump is determined at the pressure above the boiling point of the deaerator water necessary to ensure the satisfactory operation of the boiler feed pump without cavitation or instability.

Referring to Fig. 2, the same numerals are used to denote similar parts.

The condenser extraction pump 3 draws water from the condenser well 2 and discharges it through a pipe 4 whence it can pass by way of the pipe 17 to the deaerator 16, or, alternatively, by way of a pipe 34 and pressure-loaded valve 35

to the pipe 7, from which the water can flow through the float-controlled inlet valve 8 and pipe 9 to the condenser 1. In the event of a failure of the condenser extraction pump 3, the boiler feed pump 11 can draw water direct from the feed tank 5 by way of the non-return valve 12 and pipes 13 and 14. The deaerator extraction pump 28 withdraws deaerated water from the deaerator tank 25 and discharges through the non-return valve 30 and the pipe 14 to the suction of the boiler feed pump 11, which delivers the water through the pipe 29 to the boilers. The deaerator extraction pump maintains a substantially constant discharge pressure in the pipe 14 at a predetermined pressure in excess of the pressure in the deaerator 16 and in excess of the pressure from the water in the feed tank 5, so that the non-return valve 12 is kept closed at all times in normal operation and a pressure above atmosphere is maintained in the pipelines 14 and 13, whereby any possibility of ingress of air or contaminated water to the feed system is prevented and the discharge of deaerated water from the deaerator 16 back to the feed tank 5 is prevented by the non-return valve 12. On failure of the deaerator 16 or the deaerator extraction pump 28, feed water can be drawn direct from the feed tank 5 by way of the non-return valve 12 and pipes 13 and 14 to the suction of the boiler feed pump 11, thereby ensuring the continuity of the feed supply to the boilers. A non-return valve 30 is provided on the discharge of the deaerator extraction pump 28 to prevent any feed water from the feed tank 5 entering the deaerator 16 by way of the deaerator extraction pump 28 in the event of a failure of that pump. I also connect the discharge of the deaerator extraction pump to the top of the deaerator by way of pipe 31 and the pressure-loaded valve 36. The capacity of the deaerator extraction pump is equal to or greater than the boiler feed pump capacity so that in normal operation there is always a flow of water from the deaerator extraction pump 28 by way of the pipe 31 and pressure-loaded valve 36 into the deaerator 16. The water flowing in this manner is subjected to a repeated deaerating action.

Constant recirculation may be provided between the condenser extraction pump 3 and the condenser 4 by way of the pipe 37 and restriction orifice 38, so that there is in continuous circulation a predetermined quantity of water which is being subjected to a repeated deaerating action. This ensures that the water in the base of the condenser well 2 is always thoroughly deaerated. In the same way, I provide a pipe 39 with restriction orifice 40 to maintain a constant circulation of water through the deaerator so that the quantity of water in the deaerator tank 25 is always completely deaerated. The arrangement is such that two or more turbines with their respective condensing plants can be operated satisfactorily in parallel with the discharges of the respective condenser extraction pumps 3 married at a common discharge point such as 15. The arrangement further permits two or more boiler feed pumps 11 to be operated stably and satisfactorily in parallel at all loads, sharing the total load in proportion with their head capacity characteristics. All feed water which is discharged to the boilers is subjected to the double deaeration of the condenser followed by the deaerator, and in each of these units some of this feed water is subjected to repeated deaeration, thereby ensuring the removal of all

corrosive gases at all loads. Further, both the condenser extraction pump 3 and the deaerator extraction pump 28 are constrained to operate at substantially constant discharge pressures and with suction heads which are in excess of their cavitating free suction heads, thereby ensuring stability in operation, freedom from gulping, and ensuring that two or more feed systems will operate stably and satisfactorily at all loads with a minimum rise in feed pump discharge pressure from full load to no load.

The pressure-loaded valves 35 and 36 may be arranged to be automatically controlled by relay apparatus so as to maintain substantially constant discharge pressures at the discharges of the respective pumps 3 and 28.

It will be understood that the invention can be applied to three, four or more condensing plants operating in parallel and also that, while there have been illustrated and described particular arrangements in accordance with the invention, there may be employed other means other than those described to maintain substantially constant pressures at the discharges of the condenser and deaerator extraction pumps in accordance with the invention.

Referring to Fig. 2 it will be understood that the pressure applied to the surface of the water in the feed tank may be atmospheric pressure or superatmospheric pressure, e. g., of steam or gas.

What is claimed is:

1. A closed feed system for a boiler installation including a condenser for condensing the steam generated in the boiler, a deaerator for deaerating the feed water for the boiler, means including a conduit and a condenser pump therein for conducting condensate from the condenser into the deaerator, a boiler feed water pump, means including a conduit and a deaerator extraction pump therein for conducting deaerated feed water from the deaerator to the inlet of the boiler feed pump, an external feed water tank arranged to supply feed water at a superatmospheric pressure, piping connecting the external feed tank with the conduit connected to the inlet of the boiler feed water pump for supplying water to the boiler feed water pump if the deaerator extraction pump should fail, a non-return valve in said piping, said deaerator extraction pump having a discharge pressure substantially in excess of the pressure on the water in the piping from the feed water tank, whereby feed water is normally supplied to the boiler feed pump only by the deaerator extraction pump, a valve-controlled conduit for conducting water from the feed tank into the condenser, pipe means for conducting condensate from the condenser pump into said valve-controlled conduit up-stream of the valve therein, and control means operatively associated with the condenser extraction pump and the deaerator extraction pump adapted to maintain a substantially constant flow of water through said extraction pumps at substantially predetermined constant discharge pressures at the discharge outlets of said extraction pumps.

2. A closed feed system as claimed in claim 1, in which said pipe means is provided with a valve responsive to the discharge pressure of the condenser pump.

3. A closed feed system as claimed in claim 1, including an orifice-controlled pipe connected into the conduit leading from the condenser pump and into the condenser for providing a constant flow of condensate from the outlet of

the condenser pump into the condenser for deaeration therein.

4. A closed feed system for a boiler installation including a condenser for condensing the steam generated in the boiler, a deaerator for deaerating the feed water for the boiler, means including a conduit and a condenser extraction pump therein for conducting condensate from the condenser into the deaerator, a boiler feed water pump, means including a conduit and a deaerator extraction pump therein for conducting deaerated feed water from the deaerator to the inlet of the boiler feed pump, an external feed water tank arranged to supply feed water at a superatmospheric pressure, piping connecting the external feed tank with the conduit connected to the inlet of the boiler feed water pump for supplying water to the boiler feed water pump if the deaerator extraction pump should fail, a non-return valve in said piping, said deaerator extraction pump having a discharge pressure substantially in excess of the pressure on the water in the piping from the feed water tank, whereby feed water is normally supplied to the boiler feed pump only by the deaerator extraction pump, and control means operatively associated with the condenser extraction pump and the deaerator extraction pump adapted to maintain a substantially constant flow of water through said extraction pumps at substantially predetermined constant discharge pressures at the discharge outlets of said extraction pumps.

5. A closed feed system for a boiler installation including a condenser for condensing the steam generated in the boiler, a deaerator for deaerating the feed water for the boiler, means including a conduit and a condenser extraction pump therein for conducting condensate from the condenser into the deaerator, a boiler feed water pump, means including a conduit and a deaerator extraction pump therein for conducting deaerated feed water from the deaerator to the inlet of the boiler feed pump, an external feed water tank arranged to supply feed water at a superatmospheric pressure, piping connecting the external feed tank with the conduit connected to the inlet of the boiler feed water pump for supplying water to the boiler feed water pump if the deaerator extraction pump should fail, a nonreturn valve in said piping, said deaerator extraction pump having a discharge pressure substantially in excess of the pressure on the water in the piping from the feed water tank, whereby feed water is normally supplied to the boiler feed pump only by the deaerator extraction pump, an orifice-controlled pipe connecting the discharge outlet of the condenser pump with the condenser, and an orifice-controlled pipe connecting the discharge outlet of the deaerator extraction pump with the upper part of the deaerator to maintain a substantially constant flow of water through said extraction pumps at substantially predetermined constant discharge pressures at the discharge outlets of said extraction pumps.

6. In the processing of feed water to be supplied to a boiler comprising a part of the closed feed system including a condenser for the boiler, the steps comprising providing a source of boiler feed water arranged to supply feed water at a superatmospheric pressure, maintaining a body of condensate in the condenser, pumping a stream of condensate from the condenser into a deaerating zone in which the condensate is subjected to deaerating conditions and the resulting deaerated condensate accumulated in a body, pumping a

stream of deaerated condensate from said body of deaerated condensate and passing at least a portion thereof to the inlet of a boiler feed water pump, passing a stream of water from said water source into the stream of deaerated condensate flowing to the boiler feed water pump when said stream of deaerated condensate is insufficient to supply the requirements of the boiler feed water pump, and under normal operating conditions maintaining the pressure on the stream of deaerated condensate flowing to the boiler feed pump in excess of the pressure on the water from the feed water source, whereby the flow of water from the feed water source directly to the boiler feed pump is prevented.

7. The processing of feed water as claimed in claim 6 in which said source of feed water includes a hydrostatic head of water in a column providing water under superatmospheric pressure at the level of the condenser, and including the steps of passing the stream of condensate from said condenser into said column, passing condensate from said column into the deaerating zone, and passing a controlled flow of condensate from said column of water into the condenser.

8. The processing of feed water as claimed in claim 6, in which the streams of condensate and deaerated condensate are maintained at substantially predetermined constant pressures and delivered by the respective pumping operations at substantially constant rates of flow.

9. A closed feed system for a boiler installation including a condenser for condensing the steam generated in the boiler, a deaerator for deaerating the feed water for the boiler, means including a conduit and a condenser extraction pump therein for conducting condensate from the condenser into the deaerator, a boiler feed water pump, means including a conduit and a deaerator extraction pump therein for conducting deaerated feed water from the deaerator to the inlet of the boiler feed pump, an external feed water tank located at a higher level than said condenser and arranged to supply feed water at a superatmospheric pressure, piping connecting the external feed tank with the conduit connected to the inlet of the boiler feed water pump for supplying water to the boiler feed water pump if the deaerator extraction pump should fail, a non-return valve in said piping, said deaerator extraction pump having a discharge pressure substantially in excess of the pressure on the water in the piping from the feed water tank, whereby feed water is normally supplied to the boiler feed pump only by the deaerator extraction pump, a pipe connected into said piping up-stream of said non-return valve and connected into said condenser, a valve in said pipe, a float in said condenser controlling the valve in said pipe, and a water flow connection between the condenser pump conduit and a point of said piping upstream of the non-return valve therein.
